(57) **CLAIM**

The ornamental design for an arched handle for cookware lid, as shown and described.

DESCRIPTION

FIG. 1 is a perspective view of the “arched handle for cookware lid”, showing my new design;

FIG. 2 is a top plan view thereof;

FIG. 3 is a front elevational view thereof;

FIG. 4 is a bottom plan view thereof; and,

FIG. 5 is a side elevational view.

The broken lines in FIGS. 1, 2, 4, and 5 are for illustrative purposes only, depicting the environment of the new design, forming no part thereof as claimed.

1 Claim, 1 Drawing Sheet
